US0D1017119S

(12) **United States Design Patent** (10) **Patent No.:** **US D1,017,119 S**
(45) **Date of Patent:** **** Mar. 5, 2024**

(54) **ELECTRONIC CIGARETTE**

(71) Applicant: **Shenzhen Eson Biotechnology Co., Ltd.**, Shenzhen (CN)

(72) Inventors: **Daniel Chen**, Shenzhen (CN); **Jin Yang**, Shenzhen (CN)

(73) Assignee: **Shenzhen Eson Biotechnology Co., Ltd.**, Shenzhen (CN)

(**) Term: **15 Years**

(21) Appl. No.: **29/826,808**

(22) Filed: **Feb. 15, 2022**

(30) **Foreign Application Priority Data**

Nov. 4, 2021 (EM) 008747745-0001

(51) **LOC (14) Cl.** **27-07**

(57) **CLAIM**

The ornamental design for an electronic cigarette, as shown and described.

DESCRIPTION

FIG. 1 is a perspective view of an electronic cigarette, showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the electronic cigarette that form no part of the claimed design.

1 Claim, 8 Drawing Sheets
